DESIGN FOR A RUG.

SPECIFICATION forming part of Design No. 34,914, dated August 6, 1901.

Application filed July 6, 1901. Serial No. 67,366. Term of patent 8½ years.

To all whom it may concern:

Be it known that I, ERNEST H. BENNETT, a citizen of the United States, residing at East Orange, New Jersey, have invented and produced a certain new and original Design for Rugs, of which the following is a full, clear, and exact description, reference being had to the accompanying drawings, forming a part of this specification.

10 My design is applicable to and intended for the surface ornamentation of woven rugs.

In its essentials it consists, as shown in the drawings, of two parallel rectangular border-lines *a b* and between them a series of fanciful figures *c*. The field-center contains a central diamond-shaped figure *d*, with oppo-

sitely-arranged duplicates of a little more than half of the same at each corner end of said central complete figure *d*, the remaining space in the field-center being filled with a series of figures *e* of varying character.

I claim—

The design for a rug, substantially as shown and described.

In testimony whereof I have hereunto affixed my signature this 27th day of May, A. D. 1901.

ERNEST H. BENNETT.
